UNITED STATES PATENT OFFICE

172,654

CORNER ORNAMENT FOR FRAMES

Arthur Waller, Highland Park, Ill.

Application August 24, 1953, Serial No. 26,561

Term of patent 14 years

(Cl. D29—20)

To all whom it may concern:

Be it known that I, Arthur Waller, a citizen of the United States, residing at Highland Park, county of Lake, and State of Illinois, have invented a new, original, and ornamental Design for a Corner Ornament for Frames, of which the following is a specification, reference being had to the accompanying drawing, forming a part hereof, in which:

Figure 1 is a perspective view of a corner ornament for frames showing my new design;

Figure 2 is a top plan view;

Figure 3 is a side elevational view;

Figure 4 is a bottom plan view;

Figure 5 is a front end elevational view, and Figure 6 is a rear end elevational view.

I claim:

The ornamental design for a corner ornament for frames, as shown.
